O. H. ELIEL,
HERMETICALLY SEALED CASKET,
APPLICATION FILED MAR. 19, 1920.

1,369,919.

UNITED STATES PATENT OFFICE.

OSCAR H. ELIEL, OF LA SALLE, ILLINOIS.

HERMETICALLY-SEALED CASKET.

1,369,919.

Specification of Letters Patent.

Patented Mar. 1, 1921.

Application filed March 19, 1920. Serial No. 367,181.

To all whom it may concern:

Be it known that I, OSCAR H. ELIEL, a citizen of the United States, and a resident of the city of La Salle, in the county of La 5 Salle and State of Illinois, have invented certain new and useful Improvements in Hermetically-Sealed Caskets; and I do hereby declare that the following is a full, clear, and exact description of the same, 10 reference being had to the accompanying drawings, and to the numerals of reference marked thereon, which form a part of this specification.

This invention relates to a hermetically 15 sealed burial casket of a type wherein the sealing material comprises a fusible metal. Since the body must necessarily be placed in the casket before the sealing is effected, it is extremely desirable that an efficient and 20 rapid method of sealing be provided. If it is desirable to re-open a hermetically sealed casket in order to re-view the body or remove it therefrom, it is necessary that some means be provided for fusing the sealing material whereby the cover may be removed from the casket without defacing the 25 same.

It is also desirable that the fusible material, used in sealing the casket, so engage the 30 cover thereof that it acts to lock said cover securely in position on the casket.

It is an object of this invention to provide a method for hermetically sealing a casket or other container with fusible material such as fusible metal or solder.

It is also an object of this invention to provide a method for hermetically sealing a casket with electrically fused metal.

It is another object of this invention to 40 provide a hermetically sealed casket having the cover thereof securely locked in position by the sealing material.

It is an important object of this invention to provide a casket adapted to be hermetically sealed by electrically fused material and having means associated therewith whereby the sealing material may again be electrically fused after sealing.

Other and further important objects of 50 this invention will be apparent from the disclosures in the specification and the accompanying drawings.

The invention (in a preferred form) is 55 illustrated in the drawings and hereinafter more fully described.

On the drawings:

Figure 1 is a horizontal section taken through the cover of a hermetically sealed casket embodying the principles of this invention.

Fig. 2 is a section on line 2—2 of Fig. 1.

Fig. 3 is an enlarged detail section showing the method of sealing the cover of the casket to the rim thereof provided by this invention.

Fig. 4 is a section on line 4—4 of Fig. 3.

Fig. 5 is an enlarged section on line 5—5 of Fig. 1.

Fig. 6 is an enlarged detail section showing a modified method of sealing the casket 70 cover to the rim thereof.

As shown on the drawings:

The method of this invention is adapted to be used on a casket 1, which is provided with a cover 2. The vertical walls of the 75 casket 1 are bent downwardly at their upper edge and again upwardly to form a channel 3 around the rim of said casket. Downwardly extending flanges 4 are provided on the cover 2 and have integral projections 5 80 at the lower edge thereof which engage at the bottom of the channel 3. Extending along the channel 3 outside of the flange 4 is a hollow tube 6 of fusible material, preferably a fusible metal such as solder. 85 An insulating tube 7 of glass or other non-inflammable insulating material is placed inside the fusible tube 7, and, as shown in Fig. 5, the ends of said tube are bent downwardly in the space 8 between the adjacent 90 ends of the fusible tube 6. A heating element which may be composed of a strand of high-resistance wire 9 is inserted inside the insulating tube 7 and the ends of said heating element 9 extend outwardly from 95 the downwardly bent portions of said tube 7.

The operation is as follows:

The cover is placed on the casket and fusible tube 7 placed in position in the channel 3 as heretofore described. A source of 100 electrical energy such as an electrical machine or storage battery is connected to the terminals of the heating element 9 and the circuit is closed. This causes the heating element 9 to become incandescent and the 105 fusible material of the tube 7 is melted and fills the channel 3, as shown in dotted lines in Fig. 3. This fused material flows between the projections 5 and thus securely seals the projection 4 in the channel 3.

Since the insulating tube 7 is composed of non-inflammable insulating material, said tube 7 and the heating element 9 remain embedded in the fused material. After the 5 casket is thoroughly sealed by complete fusion of the tube 7, the electric circuit is opened and the source of electrical energy disconnected. If at any subsequent time it is desired to open the casket the same can 10 be easily effected without defacing the casket. This is accomplished by again connecting a source of electrical energy to the terminals of the heating element 9 and refusing the material from the tube 7. When 15 said material is fused and soft the cover 2 may be easily lifted from the casket without damaging the same and the sealing material removed from the channel 3. When it is desired to seal the casket again new 20 fusible material may be readily added or a new tube 7 supplied if necessary. As shown in Fig. 6, the casket may be hermetically sealed without the aid of electric means by simply pouring fusible material into the 25 channel 3. Said sealing material readily flows between the projections 5 on the flanges 4 and thus completely seals both sides of said flange 4 in the channel 3. While the method and construction shown applies particularly 30 to a burial casket, it is not necessarily limited to the same, but the method may be readily and effectively used in hermetically sealing any form of vessel and provides a desirable means for readily unsealing the same 35 when desired.

I am aware that numerous details of construction may be varied through a wide range without departing from the principles of this invention, and I therefore do not 40 propose limiting the patent granted otherwise than necessitated by the prior art.

I claim as my invention:

1. The combination with a casket and the

cover therefor, of means for hermetically sealing the cover on the casket, and electric 45 heating means embedded in said sealing means.

2. The combination with a casket having a channeled rim, of a cover for said casket, downwardly extending flanges on the cover 50 engaged in said channeled rim, fusible material in the channeled rim for hermetically sealing the covers thereto, and electrical means for fusing said fusible material.

3. The combination with a container hav- 55 ing a channeled rim, of a cover therefor engaged in the channel in said rim, fusible material in the channel and surrounding said cover, and an electrical heating element in the fusible material whereby said fusible 60 material may be melted and the cover hermetically sealed on the container.

4. The combination with a container hav- 65 ing a flanged rim, of a channel formed in said rim, a cover for the container engaged in the channel, fusible material in the channel adjacent the cover, an insulated electric heating element in the fusible material whereby said fusible material may be melted to seal the casket and remelted when it is 70 desired to unseal the casket.

5. The combination with a container hav- 75 ing a channeled rim, of a downwardly flanged passaged cover engaged in the channel in said rim, and a fusible metallic sub- 80 stance in the channel and engaged through the passage for sealing the cover in said channel.

In testimony whereof I have hereunto sub- 80 scribed my name in the presence of two sub- 85 scribing witnesses.

OSCAR H. ELIEL.
